No 174 Large Wooden Design for a Store Salvator & Afric 1848.

Des. 174

George W. Wood, Count of Utica, at New-York,
Letters Patent No. 174, dated April 4th, 1818.

The Schedule referred to in these letters —
Patent and making part of the same.

To all whom it may concern

Be it known, that I, George W.

Wood of Utica in the County of Oneida and State of
New York, have invented and produced a new and original
Design, Shape, Configuration and pattern of Stoves to be used in
the manufacture of Oil-light Cooking, Stoves, and I hereby de-
clare, the following, is a full and exact description of the same.
The nature of my invention consists in the frontispiece shape
and configuration of stove and ornamental work of the outer
surface of the plates forming the stove, consisting of panel work
mostly in Squares and oblongs, surrounded by raised, mouldings;
the upper plate is perfectly plain and is calculated for circular
boilers, immediately under which and in the front part of the
stove is the fire place, under and behind which and over
spying; the whole under part of the stove is the oven; the vertices
of the doors of the fire place both front and side and also of
the oven are panels formed by raised double mouldings; the
edges of the doors and also of the summer arrangement and
legs are formed by single raised mouldings.

Attached to the stove in front is a summer arrangement with
grates, flues and two circular boiler holes for cooking in summer,
which cannot be particularly described in words, but is as
well as the feet and every part of the stove accurately described
by the drawing hereunto annexed which is referred to as part
of this description —

What I claim as my invention and desire

Des. 174

24

to secure by Letters Patent is the design, shape and con-
figuration of the Stove, and the style and ornamented work
on the external surfaces of the plates and the form and
position of the Legs.
